UNITED STATES PATENT OFFICE.

THOMAS B. KIRBY, OF CHICAGO, ILLINOIS.

REFRIGERATOR-CAR LOCK.

SPECIFICATION forming part of Letters Patent No. 650,560, dated May 29, 1900.

Application filed March 11, 1899. Serial No. 708,771. (No model.)

To all whom it may concern:

Be it known that I, THOMAS B. KIRBY, of Chicago, in the county of Cook and State of Illinois, have invented certain new and useful Improvements in Refrigerator-Car Locks, of which the following is a specification.

This invention relates to refrigerator-car locks, and has for its object to provide a locking device whereby the closures of the apertures by means of which access is had to the interior of such cars may be readily closed and secured by means of suitable locking and sealing devices. The lock which I have devised is more particularly devised for use in securing the hinged doors or covers of the ice-holes of refrigerator-cars, although it is adapted for use in other locations and also for use with such doors when not hinged.

The objects more specifically in view are to provide a lock whereof the locking-bolt shall not be liable to become displaced or lost and which, while always in proper position to secure the door or cover in a locked position, will not be liable to breakage in case the door or cover is closed without the locking-bolt being withdrawn into an entirely-open position.

To these ends my invention consists in certain novel features, which I will now proceed to describe and will then particularly point out in the claims.

In the accompanying drawings, Figure 1 represents a longitudinal sectional view of a portion of a refrigerator-car having my improved lock applied to the door or cover of one of the ice-holes thereof. Fig. 2 is a plan view of the same. Fig. 3 is a plan view of the lock proper detached; Fig. 4, an end elevation thereof, and Fig. 5 a side elevation.

In the said drawings, 10 indicates the car-body, and 11 the roof thereof, having an ice-hole 12 therein, which is closed by a cover 13, hinged at 14 to the margin of the ice-hole. Upon the free margin of this cover 13 is mounted the lock, which consists of a base-plate 14, adapted to be secured to the top of the door-cover and having a vertical flange 15 to fit against the front edge thereof. This base-plate is provided with a slot 16, through which the locking-staple 17 may pass, said locking-staple being secured to the car and extending upward from the roof thereof and the cover 13 being suitably slotted, as shown at 18, to

permit the passage of said staple, the slots 16 and 18 registering. The base-plate 14 is provided with an upwardly-projecting lug 19, 55 having an aperture 20 therethrough, which when the cover is closed registers with the opening in the upper portion of the loop or staple 17.

21 indicates an arm extending forward from the flanged margin of the plate 14 and having upwardly-extending lugs 22 to receive a pivot-pin 23, upon which the locking-bolt 24 is mounted. The rear portion of this locking-bolt is shaped to adapt it to pass through the staple 17 and through the aperture 20 in the lug 19 and is itself provided with a transverse aperture 25 to receive a suitable sealing or locking device. The forward portion of the locking-bolt 24 is longitudinally slotted, as shown at 26, said slot being in a plane substantially parallel to the plane of the base-plate 14 and the pivot-pin 23 passing through said slot 26 and serving not only as a pivot-pin, but also as a guiding-pin. 75 The lugs 22 have substantially-parallel opposite faces, and the sides of the forward part of the locking-bolt 24 are plane or flattened, as indicated at 27, and this portion of the bolt is of such a width as to fit between the lugs 22, which therefore serve to guide said bolt in its longitudinal movement. The locking-bolt is also desirably provided with an upwardly-extending projection 28, by means of which it may be more conveniently moved 80 longitudinally. The under side of the forward or slotted portion of the bolt is preferably curved longitudinally, as more clearly shown in Fig. 5, and the slot 26 is preferably correspondingly curved for the purpose of 85 giving a sufficient clearance between the bolt and the adjacent surface of the arm 21 to permit the said bolt to tilt freely. The lock thus organized is secured in position upon the free edge of the cover 13, as indicated in 90 Figs. 1 and 2, and it will be noted that the locking-bolt has not only a longitudinal sliding connection with its base, but is also pivotally connected therewith, so that its free end is capable of swinging toward and from 95 said base. In using the lock to secure the door or cover in place the locking-bolt is moved longitudinally, so as to draw its free end forward clear of the slot 16, whereupon 100

the cover may be lowered into a closed position, and the locking-bolt may then be slipped backward through the staple 17, which projects upward through the slot 16, 5 said locking-bolt also extending through the opening 20 in the lug 19. A staple-securing device, such as a seal or locking device in the nature of a padlock or the like, may be then passed through the aperture 25 in the projecting end of the locking-pin, and the cover will 10 thus be secured in position. The construction set forth is particularly advantageous, for the reason that in case the locking-bolt is not retracted to a sufficient extent during 15 the lowering of the door-cover into position and does not clear the slot 16 the staple 17 when it protrudes through said slot and strikes against the end of the locking-bolt will not break or strain this latter or be itself 20 injured, as the locking-bolt will be free to move upward and permit the full closure of the door and give free passage to the staple without any damage to the parts of the lock. The bolt is, moreover, properly guided, so as 25 to be caused to accurately pass through the staple and lug when moved into a locking position, and is permanently connected to its base-plate, and therefore not liable to be lost or stolen, as is the case with locking-pins such 30 as are ordinarily employed and which are connected to the car or cover by means of a chain or the like.

I do not wish to be understood as limiting myself to the precise details of construction 35 hereinbefore set forth, as it is obvious that these details may be varied without departing from the principle of my invention. For instance, the lug 19 upon the base-plate may be omitted, although I prefer to employ the 40 same, for the reason that it not only serves to more permanently secure the parts together, but also affords a means for holding the locking-bolt in a fixed position, where it cannot 45 swing free and be liable to injury when the door or cover is open.

I claim—

1. In a car-lock, the combination, of a base, a locking-pin mounted to slide endwise on said base, a slot in said base located in alignment with, and arranged transversely with 50 relation to, said locking-pin to receive a loop or staple in position to receive the locking-pin in said endwise movement of the latter, and pivotal connections between the locking-pin and base, constructed to permit endwise 55 movement of the pin and whereby the loop-engaging end of the latter is free to swing outwardly from the base when disengaged from the loop, substantially as described.

2. In a car-lock, the combination, with a 60 base having a slot to receive a loop or a staple and provided with a transverse guiding and pivot pin, of a locking-pin longitudinally slotted at its end remote from the locking end to receive said guiding and pivot pin where- 65 by said locking end is free to swing away from the base, substantially as described.

3. In a car-lock, the combination, with a base slotted to receive a loop or staple and provided with parallel guide-lugs supporting 70 a transverse pin, of a locking-bolt adapted to fit between said lugs and slotted longitudinally at its end remote from the locking end to receive said transverse pin whereby said locking end is free to swing away from the 75 base, substantially as described.

4. A car-lock comprising a slotted base-plate having a perforated lug adjacent to said slot and parallel guiding-lugs connected by a transverse pin, in combination with a locking-pin longitudinally slotted at one end and having its other end adapted to be projected over the slot in the base-plate and through the apertured lug thereof, substantially as 80 described.

THOMAS B. KIRBY.
